H. D. POWNALL,
APPARATUS FOR PRODUCING ARTIFICIAL ICE,
APPLICATION FILED MAR. 22, 1913.

Patented Apr. 25, 1916.

1,180,535.

UNITED STATES PATENT OFFICE.

HENRY D. POWNALL, OF CANTON, OHIO.

APPARATUS FOR PRODUCING ARTIFICIAL ICE.

1,180,535.

Specification of Letters Patent. Patented Apr. 25, 1916.

Application filed March 22, 1913. Serial No. 756,248.

To all whom it may concern:

Be it known that I, HENRY D. POWNALL, a citizen of the United States, residing at Canton, in the county of Stark and State of Ohio, have invented certain new and useful 5 Improvements in Apparatus for Producing Artificial Ice, of which the following is a specification.

My invention relates to improved apparatus for producing artificial ice.

One of its objects is to provide an improved brine tank and ice mold construction of the raw water type.

Another object is to provide improved 15 means to prevent freezing in the water and air conduits leading to the ice molds.

Another object is to provide improved means to release the ice from the bottoms 20 of the ice molds.

My invention also comprises certain details of form, combination and arrangement, 25 all of which will be fully set forth in the description of the accompanying drawings in which:

Figure 1 is a top plan view of a brine tank unit embodying my invention, with the top or lids removed. Fig. 2 is an enlarged vertical section on line *z-z* of Fig. 1. Fig. 3 is an enlarged sectional detail on line *v-v* of 30 Fig. 1. Fig. 4 is a view similar to Fig. 2 of a modification.

The accompanying drawings represent the preferred embodiment of my invention in which A represents one of several counter 35 part brine tank units, in each of which are located one or more preferably a series of ice molds or containers B. As illustrated brine is supplied from a brine cooler to the tank A through a conduit 2 and circulated 40 about the side walls of the containers and then conducted back to the brine cooler through a conduit 3. A central partition 4 causes the brine to traverse a loop shaped path through the tank A. The bottom of 45 the tank is provided with perforations 5 beneath the respective ice molds, beneath which perforations are detachably secured coupling members D through which raw water and air are supplied to the ice molds. 50 The ice molds are vertically arranged rectangular sheet metal tubes having inwardly turned flanges 6 by means of which the ice molds are detachably secured by bolts 7 to

the bottom of tank A. The inturned flanges 6 may be formed by turning or bending inwardly the lower edges of the sheet metal but are preferably formed by securing angle irons to the lower edge of the sheet metal. The bolts 7 and their nuts are preferably of brass to prevent corrosion. 55

The coupling members D are provided with flanges 8 against the lower faces of which rest plates 9 while the lower portion of said coupling members project below the plates 9 and have each a raw water supply 65 conduit 10, a raw water exit conduit 11, and an air supply conduit 12, said conduits being so arranged that air supplied under pressure through conduit 12 tends to create a flow of raw water to the ice mold through 70 conduit 10, and a resulting flow of raw water charged with sediment or impurities from the ice mold through conduit 11. The air bubbles up through and agitates the raw 75 water in the ice mold and escapes at the top, and also serves to detach air bubbles and solid impurities from the face of the forming ice. As the freezing progresses, the impurities accumulate in the unfrozen water 80 and are carried away by the current through conduit 11 and conveyed to a settling reservoir, not shown, where the impurities settle out and the raw water returned to the ice molds through conduits 10.

The tank A is supported upon a metal 85 frame comprising channel bars 14 and cross bars or strips 15 riveted to members 14. The members 14 rest upon piers 16 to elevate the tank above the floor and give access to the bottom of the tank. The 90 metal plates 9 rest at one edge upon the lower flange of members 14 and at the opposite edge upon a strip or plate 17 suspended by bolts 18 from the central portion of members 15, and thereby inclose an air space 95 or chamber 19 in which the air during the freezing operation is of an even temperature slightly above freezing to prevent freezing of water in the coupling members D or the conduits leading thereto. Said chamber 19 100 also prevents excessive loss of heat from the bottom of the tank during the freezing operation.

As the brine tank is at a lower temperature than the surrounding atmosphere, there 105 is a tendency for moisture to condense upon

the exterior of the tank, and the exterior of the tank is thereby corroded, except where protected by coatings of paint, pitch or similar material. By supporting the metal tank upon a metal frame substantially as illustrated, the meeting faces of the tank and its support are reduced to a minimum, and any open spaces between the meeting edges of the tank and its support may be reached and filled with pitch or other material to prevent access of air thereto, and hence prevent the condensation of moisture and consequent corrosion at inaccessible points, while all other parts of the tank bottom are accessible to protect them from corrosion.

A series of pipes 20 are supported within the chamber 19 by hangers 21 from members 15. Said pipes 20 are connected at one end to a valve controlled supply pipe 22 and at the opposite end to a discharge pipe 23. Either steam or heated brine may be supplied through the pipe 22 by opening its valve 24 to enable the air in compartment 19 to be heated when it is desired to release the ice from the bottoms of the ice molds. This method of heating results in even and gradually applying a dry heated air to the bottoms of the ice molds, and serves to prevent too rapid heating or local heating and thereby fracture the ice, and also prevents corrosive action at the bottom of the tank or the loosening of any protective covering formed on or employed to prevent corrosion of the tank bottoms. Where steam is employed in pipes 20, I preferably employ a steam trap 26 to discharge the water condensed in said pipes, but where heated brine is employed this brine is returned from pipes 20 to the heater by means of a pipe 27 shown in dotted lines Fig. 1. If desired the air supplied to the compressor furnishing air to conduits 12 may be taken through pipe 28 to the compressor from chamber 19 thereby securing a cool air supply for conduits 12 and the air in chamber 19 replenished by conduit 29 from any pure source of air supply.

A sealing medium 40 as pitch for instance introduced in a heated or plastic condition, serves to seal the joints at the bottom of the tank and tends to retard or prevent rapid freezing of ice upon the bottoms of the ice molds. By detaching the bolts 7 and heating the lower portions of the ice molds they may be readily detached and replaced if defective, when the sealing medium reseals the joints.

In the modification Fig. 4, A' represents the tank, B' the ice molds, b the bottoms of the ice molds, 5' the openings in the bottom of the tank, D' the coupling members, 40' a sealing medium, and 19' the air chamber beneath the tank and ice mold bottoms between the frame members 14'.

The apparatus herein illustrated and described is capable of considerable modification without departing from the principle of my invention.

Having described my invention, what I claim is:

1. An artificial ice producing apparatus comprising a tank having an opening in its bottom, an ice mold seated over said opening and detachably secured to the bottom of said tank, a coupling member attached on the outside to the bottom of said ice mold to conduct water and air to said ice mold through the bottom of said tank, and a housing forming an inclosed air chamber beneath said tank and surrounding the upper portion of said coupling member.

2. An artificial ice producing apparatus comprising a tank having an opening in its bottom, an ice mold seated over said opening and detachably secured to the bottom of said tank, a coupling member attached on the outside to the bottom of said ice mold to conduct water and air to said ice mold through the bottom of said tank, a housing forming an inclosed air chamber beneath said tank and surrounding the upper portion of said coupling member, and means to heat the air within said chamber when it is desired to release the ice from the bottom of the ice mold.

3. An artificial ice producing apparatus comprising a brine tank having an opening in its bottom, an ice mold seated in said tank over said opening and detachably connected to the tank, a strata of sealing medium in the bottom of said tank surrounding the lower end of said mold, means to introduce air and water to said ice mold through its bottom, an inclosed air chamber in contact with the bottom of said tank and ice mold, and means to control the temperature of the air in said chamber.

4. An artificial ice producing apparatus comprising a brine tank having a series of openings in its bottom a plurality of ice molds in said tank seated over said openings and detachably secured in position, means to introduce air and water to said respective ice molds through said openings in the tank bottom, an enclosure forming an air chamber below and in communication with the bottoms of said tank and ice molds, and means to control the temperature in said air chamber to prevent a freezing temperature therein during the freezing operation and to release the ice from the bottoms of the ice molds.

5. An artificial ice producing apparatus comprising a brine tank having openings in its bottom, a supporting frame supporting said tank in an elevated position from the floor, ice molds in said tank seated over said openings, and detachably secured in position, means to introduce water into said ice molds

through said openings in the tank bottom, a housing carried by said supporting frame forming an air chamber in contact with the bottoms of said tank and ice molds, and 5 means to prevent a freezing temperature in said air chamber during the freezing operation.

In testimony whereof I have affixed my signature in presence of two witnesses.

HENRY D. POWNALL.
